ROTARY PUMP, COMPRESSOR, ENGINE,
AND THE LIKEMiller R. Hutchison, Jr., Madison, N. J., assignor
to Multicycol Pump & Engine Corporation,
New York, N. Y., a corporation of New York

Application January 31, 1933, Serial No. 654,420

15 Claims. (Cl. 103—124)

This invention relates to devices in the nature of rotary pumps, compressors, meters and other machines for handling or passing fluids.

Objects of the invention are to attain high working or useful displacement per revolution in a compact, simple efficient unit; to effect when so desired, continuous, as distinguished from intermittent flow; to accomplish various mixing and metering operations and to attain all the foregoing and other desirable objects in an entirely practical economical manner.

Other objects accomplished and the various novel features of construction, combinations and relations of parts involving the invention, will appear as the specification proceeds.

The drawings accompanying and forming part of the specification illustrate certain practical embodiments of the invention, but as these are primarily by way of disclosure, it will be appreciated that the structure may be further modified and changed, all within the true intent and broad scope of the invention.

Fig. 1 is a broken cross-sectional view illustrating the invention embodied in the form of a rotary pump and with direction of fluid flow indicated by arrows.

Figs. 2, 3, 4, 5 are broken end elevations illustrating the parts in successive positions, as they would appear with the end closure of the machine removed.

Fig. 6 is a broken longitudinal sectional view as on substantially the plane of line 6—6 of Fig. 1.

Figs. 7 and 8 are broken end and longitudinal sectional views illustrating a manifolding of like 35 ports by manifold passages in the end closures of the machine.

The high effective displacement per revolution is obtained in this invention through the medium of a cam-like impeller designated 9, cooperating 40 with a series of hollow faced rockers grouped about the same. This impeller cam is here illustrated as of substantially triangular formation having three flat sides 10, joined by equi-distantly spaced rounded lobes 11.

The rockers, four in number in this particular disclosure, are designated 12, 13, 14, 15 and are alike in the sense that they each having a cylindrical outer surface 16, of greater than semi-cylindrical form to seat in the greater than semi-cylindrical bearings 17, and hollow or concave inner faces 18, opposed to and cooperating with the cam contour. These concave faces may closely approach or actually follow the rounded form of the cam lobes and these concavities may merge 55 at each end into convexly rounded bearing por-

tions 19, for smoothly following the contour of the cam.

The greater than semi-cylindrical form of the bearings and rockers causes the rockers to be held in their seats without support from the cam, relieving the cam of rocker-supporting load and brings support for the rockers as close as possible to the cam following portions, the better to sustain lateral thrust and prevent binding.

The seats for the rockers are shown as formed 65 in the interior of a generally cylindrical supporting member 20, having a central cavity 21, forming a chamber for the cam and having, along the exterior of the same, channels 22, 23, 24, 25 between rocker seats and serving as passages for 70 the fluid.

In this particular illustration, the diametrically opposite channels 22 and 24 are exhaust or outlet passages and the other diametrically opposite channels 23 and 25 are inlet passages. 75

Like-functioning passages, such as outlet passages 22, 24, or inlet passages 23, 25, may be joined together or manifolded or, if desired, may be kept separate. Thus in the first form illustrated, Figs. 1 to 6, outlet passage 22 is in communication with outlet piping 26 and outlet passage 24 has connected with it outlet piping 27. Piping 26 may be led to one place and piping 27 to another, to carry fluid to separate points of use but these two lines of piping may be joined 85 at the pump or elsewhere to carry the joint supply of fluid.

Similarly, piping 28 and 29 are connected with inlet channels 23 and 25 and these may be joined to take liquid or other fluid from a single source, 90 or they may be led to separate sources of the same or different fluids. Thus the pump may be made to handle at the same time different fluids or fluids from different sources and to deliver these fluids to the same or different points of use, or to mix the fluids and deliver them together to a desired point of use. This construction also, it will be evident, enables the separate or joint handling of fluids at different heads and pressures, the mixing of fluids of different densities or other characteristics, and the like. 95

The desired valving operations are accomplished in the present disclosure by porting the rockers and rocker seats to alternately open the cavities in the rockers to the inlet and outlet 105 passages respectively. In the illustration, ports 30 extend from opposite sides of inlet channel 23, inwardly to the seats of rockers 13, 14 and similar inlet ports 31 extend through from passage 25 to the seats of adjoining rockers 12, 15. 110

From opposite sides of exhaust passages 22, ports 32 extend inwardly to the seats of rockers 12, 13 and similar exhaust ports 33 extend from exhaust passage 24 to the seats of rockers 14, 15. 5 The diametrically opposite rockers 12, 14, are shown formed with through ports 34, 35, related at acute angles to register alternately with inlet and outlet ports 31, 32 and 30, 33 and the other pair of diametrically opposite rockers 13, 15, are 10 shown as through ported at 36, 37, on obtuse angles to alternately register with inlet and outlet ports 30, 32 and 31, 33.

The operation may be traced by starting with Fig. 1, where the obtuse ported rocker 13 at the 15 top is cut off from inlet passage 23 and the acutely ported rocker 14 at the right is in full communication with inlet passage 23, by way of ports 30, 34. With the cam rotating in the direction of the arrow, the displacement chamber in the 20 face of rocker 14 is increasing in size and consequently suction is being exerted, to fill this chamber from the inlet passage. As rocker 14 turns to the right through positions, Figs. 2 and 3, the intake port 34 therein is shut off and at approximately 25 the time of maximum clearance volume, the outlet port 35 is brought into communication with outlet port 33. Then in the further rotation of the cam, through positions, Figs. 4 and 5, the liquid or other fluid within the cavity of the rocker will be displaced by the cam lobe out 30 through ports 35, 33, into outlet or exhaust passage 24. As the Fig. 5 position is reached, rocker 14 is cut off from both inlet and outlet passages and in the further movement of the cam, it 35 reverses its action to go through another cycle of taking in and discharging the fluid. Each rocker thus accomplishes a complete cycle of work for each cam lobe and as there are three lobes in the illustration, each rocker will perform three complete cycles for a single cam revolution. There 40 being four rockers, there will thus be in this particular case, twelve complete cycles accomplished for each rotation of the cam. Hence, this structure produces a high useful displacement per revolution in a particularly compact form of unit. 45

It will be noted by comparison of the different views, that both induction and discharge may be kept practically continuous. Thus, as rocker 14 approaches the end of its induction stroke as in 50 Fig. 2, the rocker 13 starts on its induction stroke, both these for a time taking from the same intake passage 23. Then, as rocker 13 approaches the end of its induction stroke, Fig. 3, rocker 12 commences to take from intake passage 25, following 55 which rocker 15, Fig. 4, commences to take from inlet passage 25 and when this rocker is about to cease its intake action, rocker 14 will again have started to draw from inlet passage 23.

Similarly as regards exhaust. Starting with 60 rocker 12, Fig. 1, which then is delivering into outlet passage 22, rocker 15 comes into action to deliver into outlet passage 24, Fig. 2, before rocker 12 cuts off. Then as indicated in Fig. 3, rocker 14 starts to deliver into outlet passage 24 and as it reaches the end of its delivery stroke, Fig. 4, rocker 13 starts delivering into outlet passage 22, Fig. 5.

The inlet and outlet passages may be manifolded or branch-connected either within or outside the machine, the external piping illustrating the possibility and practicability of the latter and Figs. 7 and 8 illustrating the carrying out of the former. In Fig. 7, the outlet passages 22, 24, are shown as cross-connected at the end of the machine by a manifold passage 38, cored or other- 75

wise formed, Fig. 8, in the end plate 39. Similarly, these views show how inlet passages 23, 25, are cross-connected by a manifolding passage 40, provided in the opposite end plate 41. In such case, only one outlet and only one inlet connection are necessary, a suitable outlet connection appearing at 42, in Fig. 7, in communication with connecting passage 38 in end plate 39. 80

While the casing of the machine may be made up in different ways, it is preferred, at present, to construct it as indicated in Figs. 6 and 8, with the end plates 39, 41, having screw connections at 43, with the ends of the outer shell 44 of the casing, this shell enclosing the cylinder 20, in which the rockers are mounted and said cylinder then serving as a means for locating the end closures in predetermined definitely spaced relation. Gaskets 45 are indicated between the end plates and the ends of the outer cylinder to prevent any leakage past the screw threads. The inside cylinder thus serves as a spacer, fixing the end clearance of the rockers and cam. By screwing up the end heads, the cylinder jacket may be preloaded in tension. This imposes a pre-compression load on the cylinder, fixing the distance between the end 95 closure surfaces, which distance will then remain constant until internal pressure against the end closure surfaces exceeds the initial tension load. The construction is easily assembled and pretensioned as described, will maintain the proper 100 end clearances through extended periods of use. 105

The cam being solid and without ports, may be formed from solid bar stock of the desired cross-section cut off the proper lengths, or may be extruded, die cast or otherwise produced. The 110 shaft of the cam which is designated 46, may be integral or separately formed and is shown as journaled in suitable bearings 47, 48, one of which may be closed as at the left in Figs. 6 and 8 and the other be open to pass the shaft for driving 115 purposes and be equipped with a suitable packing gland, such as indicated at 49. The journal portions of the end plates are shown as having hub extensions 50, to be clamped or otherwise secured by suitable mounting brackets 51 or the like. 120

To relieve the inter-rocker cavities indicated at 52 in Figs. 1 to 5, ports 53, 54, may be provided opening into the outlet and inlet passages 22, 24 and 23, 25, opposite thereto. These, it will be apparent, relieve any inter-rocker pumping action, in effect "floating" these cavities on the 125 exhaust and intake sides or lines of the pump. 130

The invention it will be seen, provides a device for pumping, metering or otherwise handling or being operated by a liquid or various liquids or fluids, which is of high capacity for its size and of simple, rugged and relatively inexpensive construction. The structure may be modified in various ways to suit different requirements and conditions, within the broad scope of the invention as will be apparent from the claims following. In view of the broad intent of the claims, it should be understood that the terms employed herein have been used in a descriptive rather than in a limiting sense, except possibly for limitations 135 as may be imposed by the state of the prior art. 140

What is claimed is:

1. A machine of the character disclosed, comprising a casing, a lobed cam operating therein, a rocker journaled in said casing and having a 145 cavitational face opposed to the cam, said casing having inlet and outlet passages and said rocker having inlet and outlet ports extending from the cavitational face of the same to communicate with the inlet and outlet passages in the casing. 150

2. A machine of the character disclosed, comprising a casing, a lobed cam operating therein, a rocker journaled in said casing and having a cavital face opposed to the cam, said casing having inlet and outlet passages, said rocker having inlet and outlet ports extending from the cavital face of the same to communicate with the inlet and outlet passages in the casing, said ports extending divergently from the cavital face of the rocker and the passages in the casing having ports spaced differently from the port spacing of the rocker. 80
- 10 3. A machine of the character disclosed, comprising a casing having a chamber therein, a lobed cam operating in said chamber, rockers journaled in said chamber about said cam and having cavital faces opposed to the cam, said casing having inlet and outlet passages at the outside of said rockers and said rockers being ported to control communication from space in the chamber between the cam and cavital faces of the rockers to said inlet and outlet passages. 85
- 20 4. A pump or the like, comprising a lobed cam, a rocker journaled to cooperate therewith and having a hollow face opposed to the cam contour, said rocker having obtusely angled ports extending from the hollow face through to the exterior of the same and a casing enclosing the cam and rocker and having intake and discharge ports opposed to the rocker and spaced a distance different than the angular spacing of the ports in the rocker. 90
- 30 5. A pump or the like, comprising a lobed cam, a rocker journaled to cooperate therewith and having a hollow face opposed to the cam contour, said rocker having obtusely angled ports extending from the hollow face through to the exterior of the same and a casing enclosing the cam and rocker and having intake and discharge ports opposed to the rocker and spaced a distance less than the angular spacing of the ports in the rocker. 95
- 40 6. A pump or the like, comprising a lobed cam, a rocker journaled to cooperate therewith and having a hollow face opposed to the cam contour, said rocker having acutely angled ports extending from the hollow face through to the exterior of the same and a casing enclosing the cam and rocker and having intake and discharge ports opposed to the rocker and spaced a distance different than the angular spacing of the ports in the rocker. 105
- 50 7. A pump or the like, comprising a lobed cam, a rocker journaled to cooperate therewith and having a hollow face opposed to the cam contour, said rocker having acutely angled ports extending from the hollow face through to the exterior of the same and a casing enclosing the cam and rocker and having intake and discharge ports opposed to the rocker and spaced a distance greater than the angular spacing of the ports in the rocker. 110
- 60 8. A pump or the like, comprising a lobed cam, hollow faced rockers cooperating therewith, certain of said rockers having acutely angled and others having obtusely angled ports extending therethrough from the hollow faces of the same and a casing enclosing the cam and rockers and having ports opposed to said rocker ports and spaced differently from the angular spacing of the rocker ports. 115
- 70 9. A pump or the like, comprising a chambered casing, rockers journaled therein and having hollow inner faces, a lobed cam cooperating with said rockers to exert pumping effect in the spaces within the hollow rockers and in the casing between adjacent rockers, valving means for con-
- trolling flow of fluid into and out of the spaces defined by the cam and hollow faces of the rockers and means for relieving the pumping effect of the inter-rocker cavity within the casing. 125
10. A pump or the like, comprising a chambered casing, rockers journaled therein and having hollow inner faces, a lobed cam cooperating with said rockers to exert pumping effect in the spaces within the hollow rockers and in the casing between adjacent rockers, valving means for controlling flow of fluid into and out of the spaces defined by the cam and hollow faces of the rockers, means for relieving the pumping effect of the inter-rocker cavity within the casing and including a port extending from the cavital space between rockers. 130
11. A pump or the like, comprising a casing, rockers journaled in said casing having hollow inner faces, a lobed cam cooperating with said hollow faced rockers to exert pumping effect in the spaces within the hollow rockers and in the casing between adjacent rockers, said casing having inlet and outlet passages, ports extending from the spaces between rockers into said inlet and outlet passages and valving means controlled by said rockers for governing flow in said passages. 135
12. A device of the character disclosed, comprising in combination, a chambered casing, rockers journaled in said casing with space therebetween, a lobed member cooperating with said rockers, said rockers having hollow faces forming with the cam member variable displacement chambers, valve means providing ingress and egress to and from said variable displacement chambers and a relief port leading from the space between said rockers. 140
13. A device of the character disclosed, comprising in combination a chambered casing, rockers journaled in spaced relation in said casing, a cam journaled in said casing, said rockers having hollow face portions engaging said cam and forming therewith variable displacement chambers, valve means providing ingress to and egress from said variable displacement chambers, inlet and outlet passages in the casing in communication with said valving means and pressure relieving ports extending from the spaces between the rockers to said inlet and outlet passages. 145
14. A machine of the character disclosed, comprising in combination a chambered casing having diametrically opposite inlet passages and diametrically opposite outlet passages, rockers journaled in said casing and having hollow inner faces ported through to communicate alternately with said inlet and outlet passages and a lobed member operating in said casing in cooperative relation with the hollow face portions of said rockers to provide variable displacement of pumping chambers. 150
15. A device of the character disclosed, comprising in combination a chambered casing having seats of generally cylindrical form disposed about a central axis, a lobed member journaled in the chamber of the casing on said axis, rockers of generally cylindrical external form journaled in said seats and having hollow inner faces opposed to and engaged by said lobed member, said rockers having ports extending therethrough from the hollow inner faces to the cylindrical outer faces of the same and inlet and outlet ports in the casing disposed for alternate registration with said rocker ports. 155
